Herbert S. Hairbank
ATTORNEY.

UNITED STATES PATENT OFFICE

HAROLD F. PAGET, OF PHILADELPHIA, PENNSYLVANIA, ASSIGNOR TO HAINES HOSIERY MILLS, INC., OF PHILADELPHIA, PENNSYLVANIA, A CORPORATION OF PENNSYLVANIA

THREAD CARRIER

Application filed January 26, 1928. Serial No. 249,601.

The object of this invention is to devise a novel construction and arrangement of a thread carrier for full-fashioned hosiery machines, which is adapted to carry a plurality of threads in spaced relationship with respect to each other. 5

With the above and other objects in view as will more clearly hereinafter appear, my invention comprehends a novel thread carrier 10 adapted to be employed in straight bar knitting machines.

It further comprehends a novel construction of a thread carrier having the usual contour of a thread carrier used in straight bar 15 knitting machines but provided with a plurality of recesses and thread receiving tubes which are arranged in spaced relationship so that reinforcing threads will be present for knitting in one or more reinforcing threads, 20 or for the purpose of ornamentation in order to form one or more stripes which may be independent of each other or contribute to form a single design.

Other novel features of construction and 25 advantage will hereinafter more clearly appear in the detailed description and the appended claims.

For the purpose of illustrating the invention, I have shown in the accompanying 30 drawings a typical embodiment of it, which, in practice, will give reliable and satisfactory results. It is, however, to be understood that this embodiment is typical only and that the various instrumentalities of which my invention 35 consists can be variously arranged and organized, and that the invention is not limited to the precise arrangement and organization of these instrumentalities as herein set forth.

40 Figure 1 is a front elevation of a thread carrier embodying my invention.

Figure 2 is a side elevation thereof.

Figure 3 is a section on line 3—3 of Figure 1.

45 Figure 4 is an end view of the thread carrier.

Similar numerals of reference indicate corresponding parts.

50 Referring to the drawings:—

The thread carrier is formed from a single

strip of material preferably of metal, and as illustrated, it consists of a flat strip 1 which forms a thread carrying finger, and at its rear end it is provided with the apertures 2 in order to receive fastening devices of the usual character to secure the thread carrier in the position to which it has been adjusted. 55

The thread carrier near its forward end is curved inwardly as at 3 and on its front face it is provided with a plurality of grooves 4 preferably arranged in parallelism. Each of these grooves 4 open through the front face of the thread carrier and at its forward end communicates with its thread receiving aperture 5 which leads to its respective thread carrying tube 6 which projects rearwardly from the forward end of the thread carrier so that the thread will be brought into close proximity with the needles. 60 65

It will be seen that I thus provide the 70 thread carrier with a plurality of thread carrying and thread spacing means and the spacing may be varied in accordance with the reinforcement or ornamentation of the stocking which is desired. 75

I have preferred to illustrate the thread carrier as having four independent thread carrying members but more or less than this number are used in practice depending upon the character of the work which is to be done. 80 The thread carrier may have its body portion formed in any desired manner and it is preferably cut away on opposite sides in order to reduce its weight. 85

It will be apparent that in accordance with 90 this invention the thread carrier is adapted to carry to the needles in spaced relationship, a plurality of threads which may be used during the knitting of the stocking to form in it stripes or medallions or ornamental figures 95 which may form independent designs or some of them be connected to form a part of the same design.

In so far as I am aware I am the first in the art to devise a thread carrier as herein disclosed and capable of performing the functions which are herein described and I therefore desire to have my claims to such features receive a broad and generic interpretation. 100

It will now be apparent that I have devised a new and useful thread carrier which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. A thread carrier for full-fashioned hosiery machines comprising a flat strip of material curved at its forward end and provided on its outer face at its forward end with a plurality of laterally spaced inclined grooves, the curved forward end having a plurality of apertures opening into said grooves and opening through said forward end, and thread carrying tubes inserted in said apertures and communicating with said grooves.

2. A thread carrier for full-fashioned hosiery machines comprising a flat strip of material curved at its forward end and provided on its outer face at its forward end with a plurality of laterally spaced inclined grooves, the curved forward end having a plurality of apertures opening into said grooves and opening through said forward end, and thread carrying tubes inserted in said apertures and communicating with said grooves, said tubes inclining rearwardly and projecting beyond the forward end of the strip to bring the threads into close proximity to the needles.

HAROLD F. PAGET.
